DESIGN FOR A COFFEE MAKER STAND

Harper Richards, Chicago, Ill., assignor to Cory Corporation, Chicago, Ill., a corporation of Delaware

Application February 17, 1947, Serial No. 136,947

Term of patent 14 years

(Cl. D44—26)

To all whom it may concern:

Be it known that I, Harper Richards, a citizen of the United States, residing at Chicago, in the county of Cook and State of Illinois, have invented a new, original, and ornamental Design for Coffee Maker Stands, of which the following is a specification, reference being had to the accompanying drawing, forming part thereof, wherein—

Fig. 1 is a perspective view, looking toward the front and one end, of a coffee maker stand, showing my new design;

Fig. 2 is an end elevation thereof; and

Fig. 3 is a horizontal section therethrough taken approximately on line 3—3 of Fig. 1.

I claim:

The ornamental design for a coffee maker stand, as shown.

HARPER RICHARDS.
